UNITED STATES PATENT OFFICE.

NOYES B. ALLYN, OF HARTFORD, CONNECTICUT.

DESIGN FOR A CLAW HAMMER OR HATCHET.

SPECIFICATION forming part of Design No. 15,422, dated September 23, 1884.

Application filed June 25, 1884. Term of patent 14 years.

To all whom it may concern:

Be it known that I, NOYES B. ALLYN, of the city and county of Hartford, and State of Connecticut, have invented a new and original 5 Design for a Nail-Pulling Claw Hammer or Hatchet, of which the following is a specification.

My design relates to the nail-pulling claws of hammers, hatchets, or hammers and hatchets combined; and it consists in a novel configuration of the jaws of the claw, as herein-after shown and described.

Reference is to be had to the accompanying drawings, forming a part of this specification, in which Figure 1 represents a view in perspective of a combined grocer's hatchet and hammer with claw having my new design. Fig. 2 is an inside face view upon a larger scale of the nail-puller detached.

20 A indicates the bifurcated nail-pulling claw, of the usual bowed or curved form in direction of its length, but having the opposite exterior sides, *a a*, of its jaws made flat and beveling or sloping, the same converging in an

outer direction transversely of the claw, and 25 so that said two sides, *a a*, present flat or straight faces at right angles with one another transversely of the claw, and the two jaws assume the figure of two reversely-inclining wedges, tapering both externally and internally, 30 but always having their outer sides, *a a*, flat and at right angles with one another.

I claim—

The design for a hammer or hatchet herein described, which consists in the bifurcated 35 nail-pulling claw of bowed or curvilinear form in the direction of its length, with its jaws having the shape in transverse section of two reversely-inclining wedges of practically uniform transverse dimensions, having flat outer 40 sides, *a a*, extending in parallel relation and in planes at right angles with one another, as shown.

NOYES B. ALLYN.
